UNITED STATES PATENT OFFICE.

NORMAN DODGE, OF EAST ORANGE, NEW JERSEY, ASSIGNEE TO MERGENTHALER,
LINOTYPE COMPANY, A CORPORATION OF NEW YORK.

TYPOGRAPHICAL MACHINE.

1,186,564.

Specification of Letters Patent. Patented Apr. 20, 1915.

Application filed July 5, 1913. Serial No. 777,572.

To all whom it may concern:

Be it known that I, Norman Dodge, a citizen of the United States, residing at East Orange, in the county of Essex, and State of New Jersey, have invented certain new and useful improvements in Typographical Machines, of which the following is a specification, reference being had thereto in the accompanying drawing.

10 My invention relates to typographical machines, such as Linotype machines of the general organization represented in Letters Patent of the United States No. 136,522, to O. Mergenthaler, wherein circulating

15 matrices are released from a magazine in the order in which their characters are to appear in print and then assembled in line, the composed line transferred to the face of a mold, the mold filled with molten metal to form a slug or Linotype against the matrices which produce the type characters thereon, and the matrices thereby released through a distributing mechanism to the magazine from which they started.

20 More particularly, it relates to that style of typographical machine equipped with a plurality of magazines and shifting means therefor, whereby any selected one thereof may be brought into operative relation to 25 the assembling devices and distributing mechanism.

One of the principal features of my invention is the division of the plurality of magazines into separate sets, each set being 30 arranged so that it is independently movable in order that each magazine therein may be brought into and out of operative position without disturbing or moving the magazines of another set, and in the preferred form specifically illustrated, so that any selected magazine of one set may be combined with any selected magazine of another set, to produce mixed matter according to the respective magazines in 35 joint action.

40 In the accompanying drawings, I have illustrated my invention in preferred form and by way of example, and as applied to a Linotype machine. Obviously, many variations and alterations may be made therein, and in its mode of application, which will still be comprised within its spirit and it may similarly be adapted to other forms of typographical machines, such as hand type or dies instead of matrices.

Generally speaking, I desire it to be understood that I do not limit myself to any specific form or construction, except in so far as such limitations are specified in the claims.

45 In the accompanying drawings; Figure 1 is a side view, partly in section and broken away, of a portion of a Linotype machine, having my invention applied thereto; Fig. 2 is a somewhat similar view, partly in section, showing the parts in different position; Fig. 3 is a section on the line 3-3 of Fig. 2; and Fig. 4 is a sectional detail.

50 For purposes of illustration, I have shown four magazines, 1, 2, 3 and 4, divided into two distinct sets, 1 and 2 supported in the shift frame A, and 3 and 4 in the shift frame B, whereby either magazine of the first set may be brought into operative relation to the assembling throat C, and either magazine of the second set into operative relation to the throat D, the throats C and D being arranged to deliver the matrices to the belt E, whereby in turn they are transferred to the other assembling devices, 55 as illustrated in the Mergenthaler patent previously mentioned.

After the line is cast and the matrices are elevated, they are delivered to the font separating means H, and by it to the respective individual distributors H' and H'', it being noted that these distributors are located in proper position to cooperate with the magazines in operative relation to the assembling throats C and D respectively. 60 The particular form of the font separating means H and the distributor H' and H'', constitute no part of my present invention, although preferably they are similar to those illustrated in Letters Patent of the United States to John R. Rogers, No. 848,771.

65 Each of the magazines is provided with its own series of escapements F, so arranged that when a magazine is brought into action, its escapements are in position to be actuated by the bars G, which in turn are operated by the levers G' and rods G'' from the customary keyboard apparatus controlled by the keys G''. The bars G are adapted to actuate the escapements of either of the magazines in action, being laterally movable so as to be connected either with the escapements of the upper magazine or the escapements of the lower magazine at will. Any suitable means may be employed 70

for this purpose, such as the rock shafts G^4 , which may be manipulated so as to connect the bars G with either set of escapements, or to disconnect them both to permit the free and unimpeded movement of the magazines, all in the manner well understood in the art.

Either of the magazines 1 and 2 of the upper set may be brought into operative position simultaneously with either of the magazines 3 or 4 of the lower set, this result being secured by the independent adjustment of the respective shift frames A and B. For instance, magazines 2 and 3 are shown in action in Fig. 1, and magazines 1 and 4 in action in Fig. 2. Any suitable means may be employed for this adjustment of the shift frames. In the drawings, I have shown the frame A as connected to the longitudinally movable plunger or cylinder J, and the frame B to the plunger K located within the cylinder J. The cylinder J is moved longitudinally by the screw J' revolvably mounted in the main frame T and engaging the lug J^2 on the cylinder, and the plunger K by the similarly mounted revolvable screw K' engaging directly therewith. The screws J' and K' are respectively provided at their lower ends with the bevel pinions J^2 and K^2 (see also Fig. 4), adapted to be engaged and operated by the double-faced bevel pinion L, mounted on the shaft M and connected thereto by a spline so as to be moved into engagement with either of the pinions J^2 or K^2 as may be desired. The shaft M is shown as angularly located and connected at one end to the shaft M' , which may be rotated when desired by the handle N, whereby one or the other of the frames A and B may be shifted.

The means for engaging the actuating pinion L with the pinions J^2 and K^2 preferably comprise the hand lever O, link O' , and pivoted lever O^2 engaging the hub L' of the pinion L, in such manner that the movement of the lever O in opposite directions connects the pinion L with either the pinion J^2 or pinion K^2 , and permits the elevation or depression of the connected shift frame by the manipulation of the handle N, to bring the selected magazine into operative relation to the corresponding assembling and distributing mechanisms.

Any suitable means may be employed for registering and locking the selected magazines in position, such for instance, as those presented in the application for Letters Patent of John R. Rogers, Serial No. 624,426. To demonstrate this capability, I have shown the lower shift frame B as adapted to be engaged by the longitudinally movable locking rod P, which is operated through the connections Q by the endwise movement of the handle N, all as set forth in the said Rogers application. For purposes of sim-

plicity of illustration, such registering and locking devices are not shown as applied to the upper shift frame A, but obviously may be applied thereto if desired.

As previously stated, I have shown my invention only in preferred form and by way of example, and obviously many modifications and changes therein, and in its mode of adaptation, will suggest themselves to those skilled in the art without departure from its scope.

Having thus described my invention, its construction and mode of operation, what I claim and desire to secure by Letters Patent of the United States, is as follows:

1. In a typographical machine, the combination of two sets of magazines, each set comprising a plurality of magazines and being movable independently of the other to effect a change from one magazine to another as to operative position; whereby different pairs of magazines may be selected for conjoint use.

2. In a typographical machine, the combination of a plurality of magazines arranged in series and divided into sets, and supporting frames, one for each set, the said frames being movable independently of each other to effect a change from one magazine to another.

3. In a typographical machine, the combination of a plurality of sets of magazines, and means for moving said sets, one independently of another, to effect a change from one magazine to another.

4. In a typographical machine, the combination of a plurality of sets of magazines, a supporting frame for each set, and means for moving said frames independently of each other to effect a change from one magazine to another.

5. In a typographical machine, the combination of a plurality of magazines divided into independent sets one overlying another, and means for moving said sets bodily with reference to each other to effect a change from one magazine to another.

6. In a typographical machine, the combination of a plurality of magazines arranged in series and divided into sets one overlying another, and a supporting frame for each set, the said frames being movable bodily toward and from each other to effect a change from one magazine to another.

7. In a typographical machine, the combination of a plurality of sets of magazines, separate adjusting means for moving said sets independently, and common operating devices for said adjusting means.

8. In a typographical machine, the combination of a series of movable magazines divided into sets, each set comprising a plurality of magazines, an assembler entrance for each set of magazines adapted to cooperate with only one magazine therein at a

time, and means for moving said sets independently in order to bring different magazines of the respective sets into operative relation to the corresponding assembler entrances.

9. In a typographical machine, the combination of a plurality of assembler entrances each adapted to coöperate with only one magazine at a time, and a separate set of magazines for each of the assembler entrances, each set being shiftable independently to bring different magazines therein into operative relation to the corresponding assembler entrance.

10. In a typographical machine, the combination of a plurality of assembler entrances each adapted to coöperate with only one magazine at a time, and a series of magazines divided into a corresponding plurality of sets, each set comprising a plurality of magazines and movable independently to bring different magazines therein into operative relation to the corresponding assembler entrance.

11. In a typographical machine, the combination of a plurality of distributing mechanisms, a corresponding plurality of assembler entrances, and a series of magazines divided into a corresponding plurality of sets, each set comprising a plurality of magazines and movable independently in order to bring any selected magazine therein into operative relation to its corresponding distributing mechanism and assembler entrance.

12. In a typographical machine, the combination of a series of magazines divided into sets, each comprising a plurality of magazines, and a plurality of distributing mechanisms, one for each set, the said sets being movable independently of each other to bring one or another of the magazines therein into operative relation to the corresponding distributing mechanism.

13. In a typographical machine, the combination of a plurality of distributing mechanisms, and a corresponding plurality of sets of magazines, said sets being movable one relatively to another, to bring different selected magazines into operative relation to the several distributing mechanisms.

14. In a typographical machine, the combination of a plurality of assembler entrances, and a corresponding plurality of sets of magazines, said sets being movable one relatively to another, to bring different selected magazines into operative relation to the several assembler entrances.

15. In a typographical machine, the combination of two sets of magazines arranged so that a magazine of one set may be used conjointly with one of the other set, one of said sets comprising a plurality of magazines and movable independently of the

other to bring a different magazine into operative position.

16. In a typographical machine, the combination of a plurality of distributing mechanisms, and a corresponding plurality of sets of magazines, one of said sets comprising a plurality of magazines, and movable independently of another set, to bring one or another of its magazines into operative relation to the corresponding distributing mechanism.

17. In a typographical machine, the combination of a plurality of assembler entrances, and a corresponding plurality of sets of magazines, one of said sets comprising a plurality of magazines, and movable independently of another set, to bring one or another of its magazines into operative relation to the corresponding assembler entrance.

18. In a typographical machine, the combination of distributing mechanism, and a plurality of sets of magazines, one of said sets comprising a plurality of magazines and movable independently of another set to bring one or another of its magazines into operative relation to the distributing mechanism.

19. In a typographical machine, the combination of assembling mechanism, and a plurality of sets of magazines, one of said sets comprising a plurality of magazines and movable independently of another set to bring one or another of its magazines into operative relation to the assembling mechanism.

20. In a typographical machine, the combination of distributing mechanism, and a plurality of sets of magazines, each of said sets comprising a plurality of magazines and movable independently of another set to bring one or another of its magazines into operative relation to the distributing mechanism.

21. In a typographical machine, the combination of assembling mechanism, and a plurality of sets of magazines, each of said sets comprising a plurality of magazines and movable independently of another set to bring one or another of its magazines into operative relation to the assembling mechanism.

22. In a typographical machine, the combination of distributing mechanism, magazines each having a series of matrix channels, and divided into sets, one of said sets comprising a plurality of magazines, and mechanism for moving said set independently of another set to connect one or another of its magazines to the distributing mechanism.

23. In a typographical machine, the combination of assembling mechanism, a plurality of sets of magazines, one set comprising a plurality of magazines, and mecha-

nism whereby one or another of the magazines in said set may be connected to the assembling mechanism without disturbing the connection of a magazine of another set to 5 the assembling mechanism.

24. In a typographical machine, the combination of two distributing mechanisms, and two sets of magazines, one of said sets comprising a plurality of magazines, and 10 the said set and its corresponding distributing mechanism being relatively movable to connect one or another of the magazines therein with the distributing mechanism without disturbing the relation between the 15 other set and its distributing mechanism.

25. In a typographical machine, the combination of two assembler entrances, and two sets of magazines, one of said sets comprising a plurality of magazines, and the said 20 set and its corresponding assembler entrance being relatively movable to connect one or another of the magazines therein with the assembler entrance, without disturbing the relation between the other set and its assembler entrance.

26. In a typographical machine, the combination of two sets of magazines each provided with escapements, the several sets being movable independently of each other to bring one or another pair of magazines into 30 operative position, and devices for actuating the escapements of the selected pair.

27. In a typographical machine, the com-

bination of a plurality of superposed magazines, divided into sets which are movable 35 relatively to each other to bring one or another pair of magazines into operative position, a series of escapements for each of the magazines, and devices for actuating the escapements of the pair in operative position. 40

28. In a typographical machine, the combination of two sets of magazines movable independently of each other to bring one or another pair of magazines into operative position, a keyboard mechanism common to 45 both sets of magazines, and means for connecting the keyboard mechanism to one or the other of the magazines of the selected pair.

29. In a typographic machine, the combination of a plurality of magazines usable in pairs, and each provided with escapements, the said magazines being movably arranged so as to effect a change from one pair to another, and a single series of devices for actuating the escapements of the two selected magazines, the said devices being mounted so as to be movable into engagement with the escapements of one or another of said magazines as required. 50

In testimony whereof I have affixed my signature in presence of two witnesses.

NORMAN DODGE.
